UNITED STATES PATENT OFFICE.

EDWARD H. WEATHERHEAD, OF CLEVELAND, OHIO, ASSIGNOR TO THE BISHOP-BAB-COCK-BECKER COMPANY, OF CLEVELAND, OHIO, A CORPORATION OF OHIO.

FILLING MACHINE.

Application filed October 13, 1916. Serial No. 125,376.

To all whom it may concern:

Be it known that I, EDWARD H. WEATHERHEAD, a citizen of the United States, and a resident of Cleveland, county of Cuyahoga, 5 and State of Ohio, have invented a new and useful Improvement in Filling Machines, of which the following is a specification, the principle of the invention being herein explained and the best mode in which I have 10 contemplated applying that principle, so as to distinguish it from other inventions.

The present improvements relating, as indicated, to a filling machine, have more particular regard to a device for filling bottles with syrup or other liquid prior to the introduction into the bottles of the greater portion of the liquid with which they are to be filled. Thus in the filling of bottles with ginger ale, root beer or other soft drinks, it 20 is customary to first supply one or more ounces of concentrated extract in one machine, and then to transfer the bottles to another machine, in which they are completely filled with plain or charged water to make 25 the desired beverage. The present invention consists of a machine for thus preliminarily filling the bottles with one or more ounces of syrup. To the accomplishment 30 of the foregoing and related ends, said invention, then, consists of the means herein-after fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—

Figure 1 is a side elevation of my improved machine shown partially in section; Figure 2 is an enlarged sectional view of the syrup compartment and operating mechanism for filling, shown in their normal positions; Figure 3 is a section on line 3—3 in Figure 2; Figure 4 is a similar section, but with the valve in a different position; Figure 5 is a side elevation of the valve; Figure 6 is a section taken on the same plane as Figure 2, but showing the valve in the position shown in Figure 4; Figure 7 is a section through the valve taken on the line 7—7 in Figure 2; Figure 8 is a section of the valve on the line 8—8 in Figure 6; Figure 9 is a section of the valve on the line 9—9 in Fig-

ure 6 and Figures 10 and 11 are other sections of the valve showing the same in different operative positions, these sections being taken on the line 9—9 in Figure 6.

Referring now to Figure 1; the machine 60 consists of a base 1 upon which are mounted uprights 2, constituting a framework. Centrally mounted in such base is a vertically disposed support 3, upon which there is rotatably mounted a series of vertically movable supports or bottle holders 4. These bottle holders are movable vertically by means of a piston 5 operating in a cylinder 6, which is connected at both its upper and lower ends with a source of fluid pressure supply 70 by means of conduits 7 and 8 respectively. The bottle holders or lifts rest normally upon a supporting table 60 suitably mounted upon the central support 3. It will be seen that the general construction of the machine is similar to that of the well-known rotary filling machine, and hence the details of construction need not be gone into.

Attached to the support 3, which is rotatable, are a plurality of laterally extending arms 9; each of which carries a filling bell mouth 10 of the usual shape, these filling bell mouths 10 being mounted vertically above the various bottle holders 4. Extending upward from the central support 3 is a liquid or a syrup conduit 11 which is fixed against rotation, and to which is connected an elbow 12 leading to another conduit 13, which is connected by means of various valves 14, 15 and 16 to chambers or reservoirs containing various kinds of liquids such as syrups. Extending through the conduit 11 is a fluid pressure supply conduit 17, which is connected at its upper end to a suitable source of fluid pressure supply and which connects at its lower end to a lateral conduit 18 which is branched and leads to either end of cylinder 6. The lower end of the cylinder 6, that is the space below the piston in the same, is always connected with conduit 8, but the upper part of this cylinder is normally disconnected from the conduit 18 by means of a valve 20 rotatably mounted in the filling arm 9.

The syrup supply conduit 11 connects by means of a passage 21 with the upper part of a syrup dispensing chamber or cylinder 22, which is mounted in the filling arm 9 directly above the bell mouth 10. The upper part of this syrup chamber 22 is con-

5 nected to the lower part by means of the passage 23, which may be opened or closed as desired by means of the valve 20, as is shown in Figures 3 and 4. Operating in the cylinder 22 is a piston 25, which is connected to a second piston 26 operating in a second and aligned cylinder 27, which in turn is connected direct to a larger piston 28 operating in a third cylinder 29. This last-named cylinder 29 is connected at its upper 10 end to the air supply conduit 17 by means of a pipe 30. The upper position of the piston 28, and hence of the pistons 26 and 25, which are connected thereto, is limited 15 by means of a stop in the form of an adjustable rod 31. This rod 31 extends beyond the cylinder 29 and such extending portion is marked off as shown in Figure 2 by lines which represent ounces of syrup admitted to the dispensing chamber 25. In this 20 way an operator can accurately control the amount of syrup supplied to each bottle of the dispensing chamber.

25 The cylinder 29 is at all times connected by means of a passage 90 with the air supply conduit 18. By this system of passages a differential action is secured in the cylinder 29 as follows:

30 When air is admitted above the piston 28 the piston is forced down, since the air pressure is acting down on the upper surfaces of pistons 26 and 28, and up only on the bottom surface of piston 28. When the air pressure above the piston 28 is discharged, then the pressure between pistons 35 26 and 28 will exert a differential action or pressure on the upper piston to raise both.

35 The normal position of the machine is shown in Figures 1 and 2. Assuming that a bottle is in position on the holder 4 when the machine has rotated through a certain distance, an arm 35, attached to the valve 20, is operated by means of a member 36. Before this operation the valve 20 is in the

40 position shown in Figures 2 and 3, and the new position of the valve is shown in Figures 4 and 6. The valve opening device 36 is shown at the right of Fig. 1, which comprises a frame 50 having a pivotal lever 51 and an arm 52 attached thereto, the end 53 of which normally projects into the path of a bottle as it reaches a position opposite this opening device. The rod 52 is held in this position by means of a coiled spring 54

55 pressing a plunger 55 out of engagement with the cam or valve operating arm 35. A bottle on the stirrup however acts to press the rod 52 outwardly and force the plunger 55 inwardly into the path of the arm 35.

60 Means, illustrated at the left in Fig. 1, as an adjustable cam lug 56 projecting into the path of the arm 35, when the valve 20 is open, is employed to actuate said arm to return the valve to its normally closed position.

65 After the valve 20 has been operated and moved into position as shown in Figures 4 and 6, the various parts of the machine are operated to supply syrup in a measured amount to the bottle. When a valve is 70 moved in the manner just described, the piston 5 is raised in the cylinder 6, since the air pressure in the latter is then allowed to escape through the passage 7 into an intermediate connection 40 in the valve 20 75 to the atmosphere. By thus exhausting the pressure above the piston in the cylinder 6 the air pressure below the same is enabled to lift the piston and with it the bottle holder 4 forcing with it a bottle into the 80 bell mouth 10. This exhaust of air from cylinder 6 is made slightly in advance of the admittance of air to the cylinder 29, as best shown in Figs. 8 and 9 in which the exhaust passage 40 is provided with a lateral 85 offset 100 which will allow the air above the piston 5 to exhaust slightly ahead of the admission of air to cylinder 29 as the valve is rotated in a counter clockwise direction. These two actions follow so rapidly that the 90 operation is almost simultaneous but the difference in time is just sufficient to allow the bottle to actually reach its position in the bell mouth before the syrup begins to flow into the bottle.

95 When the bottle is so positioned in the filling spout, air pressure is admitted to the top of the cylinder 29 through the passages 30, 43, 18, 17 and a passage 41 formed in the valve. This air pressure on the top of the 100 piston 28 forces down this piston and also forces down the piston 25 which acts upon the syrup in the chamber 22 to discharge the same through a passage 81 formed in the valve and connecting with the spout.

105 When the bottle is thus filled, the machine has rotated to such a point that a second cam operates against the arm or trip 35 to return the same to its normal position, thus moving the valve back to the position shown 110 in Figures 1, 2 and 3. The filling bell mouth 10 is formed with an undercut recess 61, thus providing a shoulder against which is placed a collar 62 disposed slidably about the filling tube and normally maintained in contact 115 with such shoulder by means of a spring 63. When a bottle is positioned in the spout it forces up the collar 62 and compresses the spring 63. The compression of the spring is sufficient to overcome the sticking of the bottle in the spout due largely to the syrup, when the bottle lift starts to fall. Upon this return movement of the valve the escape of air from the upper part of the cylinder is cut off by the valve and air pressure being admitted to the cylinder through a passage 43 connecting with an intermediate passage 44 in the valve. The pressure is balanced on both sides of the piston 5, except for the cross-sectional area of the

rod attached to the lower side of the piston 5 which causes a greater pressure against the upper side, this excess pressure forcing the piston down.

At the same time the passage 30 leading from the top of the cylinder 29 is connected to the atmosphere through a passage 45 in the valve, thus permitting the pressure on the under side of the piston 28 to raise this

10 piston and also the piston 25 in the syrup chamber. Such movement of the piston 25 will draw syrup through the passage 23 and through the valve 20 (see Figure 3) into the syrup chamber 22. On the piston 25
15 there is formed an annular rib 91 which seats in the lowest position of the piston upon a washer 92 which is placed upon the bottom of the cylinder 22, this rib acting as a valve to prevent any leakage of syrup past the piston when the piston is in its lowermost or filling position. By using this rib and washer, it is unnecessary to provide any packing for the piston itself.

Other modes of applying the principle of
25 my invention may be employed instead of the one explained, change being made as regards the mechanism herein disclosed, provided the means stated by any of the following claims or the equivalent of such stated
30 means be employed.

I therefore particularly point out and distinctly claim as my invention:—

1. In a syruping machine, the combination of a plurality of radially arranged
35 horizontally disposed rotatable filling arms, each arm being a single member and being provided with separate passages for syrup and syrup discharging fluid pressure, a centrally disposed syrup supply conduit
40 connecting with such syrup supply passages in said arms, a fluid pressure supply conduit disposed centrally within said syrup supply

conduit and connecting with such fluid pressure passages in said arms, a plurality of syrup supply reservoirs connected to said syrup supply conduit, and means for effecting disconnection of each of said syrup supply reservoirs from said syrup supply conduit.

2. In a syruping machine, the combination of a plurality of radially arranged, horizontally disposed rotatable filling arms, each arm being a single member and being provided with separate passages for syrup and syrup discharging fluid pressure, and having mechanical means operable by fluid pressure to discharge syrup, a centrally disposed syrup conduit connecting with such syrup supply passages in said arms, a fluid pressure supply conduit disposed centrally within said syrup supply conduit and connecting with such fluid pressure passages in said arms to operate said mechanical means, a source of syrup supply and means for connecting the same with said syrup supply conduit. 65

3. In a measuring and discharging device, the combination of a liquid cylinder having closed ends and capable of connection to a source of liquid, a source of liquid supply, 70 mechanically-operated valve means adapted to connect said cylinder to said supply, a piston in said cylinder and a passage connecting the two ends thereof whereby liquid may first be drawn into one end and then transferred to the other and then discharged therefrom, said piston and the walls of said cylinder being thereby immersed in such liquid at all times.

Signed by me, this 9th day of May, 1916.
EDWARD H. WEATHERHEAD.
